UNITED STATES PATENT OFFICE

EMIL G. ZULLIG, OF BERGENFIELD, NEW JERSEY, ASSIGNOR TO SAMUEL ELLEN, OF NEW YORK, N. Y.

DESIGN FOR AN EMBROIDERED TEXTILE FABRIC TRIMMING

Application filed February 10, 1933. Serial No. 47,177. Term of patent 3½ years.

To all whom it may concern:

Be it known that I, EMIL G. ZULLIG, a citizen of the United States, residing in Bergenfield, in the county of Bergen and State of New Jersey, have invented a new, original, and ornamental Design for an Embroidered Textile Fabric Trimming, of which the following is a specification, reference being had to the accompanying drawing, forming part thereof.

The figure is a plan view of an embroidered textile fabric trimming showing my new design.

The portion illustrated represents one-half of the design, which is repeated in the other half outlined by the dot and dash lines.

I claim:

The ornamental design for an embroidered textile fabric trimming substantially as shown and described.

EMIL G. ZULLIG.
